UNITED STATES PATENT OFFICE.

BAXTER CLAUDIUS SCOTT, OF PICKENS, MISSISSIPPI.

DENTURE.

Application filed November 9, 1926. Serial No. 147,350.

This invention aims to provide a novel means whereby artificial teeth may be anchored to plates or other dentures.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in plan, a set of teeth connected together by the anchoring means forming the subject matter of this application;

Figure 2 is a sectional view wherein part of the teeth and part of the anchoring means appear;

Figure 3 is a section on the line 3—3 of Figure 1;

Figure 4 is a section on the line 4—4 of Figure 1;

Figure 5 is a perspective view showing the anchoring means per se.

The device forming the subject matter of this application includes an anchor embodying a single piece of material, preferably aluminum wear, and in any event, such material as will not corrode or decompose in the denture or in the fluids of the mouth of the wearer. The piece of material above alluded to is formed into a curved body 1, comprising side members 2, and an intermediate portion 3. The side members 2 are reversely extended, as at 4, to form forwardly prolonged portions 5, the forwardly prolonged portions 5 being fashioned into alternating main loops 6, and auxiliary loops 7. The auxiliary loops 7 are engaged about the side members 2, and the ends of the forwardly extended portions 5 are connected as at 8, by twisting or otherwise, to the side members 2.

Rear teeth 9 are supplied, the teeth 9 having openings 10 through which the side members 2 pass, the main loops 6 extending about the teeth 9 and being spaced, as at 11, far enough from the surfaces 12 of the teeth

9 to afford an anchorage for the teeth 9 in a plate 14 or the like.

The device is further characterized by the provision of a second piece 15 of metal, such as aluminum or the like, the piece 15 being extended along the intermediate portion 3 of the body 1, in parallel relation thereto, the piece 15 of material has its ends located closely together, as shown in Figure 5, one of its ends 16 being engaged about the intermediate portion 3 of the body, and the other of its ends 17 being engaged with the intermediate portion 3 of the body and with the second piece 15 of material, the said second piece 15 of material being formed into alternating primary loops 18 and secondary loops 19, the secondary loops 19 being engaged about the intermediate portion 3 of the body 1 and about the second piece 15 of material.

Forward teeth 20 are provided, and have openings 21 receiving the intermediate portion 3 of the body 1 and receiving the second piece 15 of material, the primary loops 18 being spaced as at 22 from the surfaces 23 of the forward teeth 20, to afford an anchorage for the teeth 20 in the plate 14 or other denture.

The device is simple in construction, but it affords an adequate and efficient means whereby artificial teeth may be anchored in dentures of any kind. The device renders unnecessary the use of platinum pins, backings and the like. A set of teeth anchored in accordance with the invention, will be held firmly in the denture, and will not become loose under any conditions which may be imposed reasonably upon an artificial tooth.

What is claimed is:—

1. In a device of the class described, an anchor embodying a single piece of material formed into a curved body comprising side members and an intermediate portion, the side members being reversely extended to form forwardly prolonged portions, the forwardly prolonged portions being fashioned into alternating main and auxiliary loops, the auxiliary loops being engaged about the side members, rear teeth having openings through which the side members pass, the main loops extending about the rear teeth and being spaced far enough from the surfaces of the rear teeth to afford an anchorage for the teeth in a denture, and a second piece of material extended along the

intermediate portion of the body and having alternating primary and secondary loops, the secondary loops being engaged about the intermediate portion of the body, and forward teeth having openings receiving the second piece of material, the primary loops being spaced from the surfaces of the forward teeth to afford an anchorage for the forward teeth in a denture.

2. In a device of the class described, an anchor embodying a single piece of material formed into a curved body comprising side members and an intermediate portion, the side members being reversely extended to form forwardly prolonged portions, the forwardly prolonged portions being fashioned into alternating main and auxiliary loops, the auxiliary loops being engaged about the side members, rear teeth having openings through which the side members pass, the main loops extending about the rear teeth and being spaced far enough from the surfaces of the rear teeth to afford an anchorage for the teeth in a denture, and a second piece of material extended along the intermediate portion of the body, the said second piece of material being formed into alternating primary and secondary loops, the secondary loops being engaged about the intermediate portion of the body and about the second piece of material, and forward teeth having openings receiving the intermediate portion of the body and the second piece of material, the primary loops being spaced sufficiently from the surface of the forward teeth to afford an anchorage for the forward teeth in a denture.

3. In a device of the class described, an anchor embodying a single piece of material formed into a curved body comprising side members and an intermediate portion, the side members being reversely extended to form forwardly prolonged portions, the forwardly prolonged portions being fashioned into alternating main and auxiliary loops, the auxiliary loops being engaged about the side members, rear teeth having openings through which the side members pass, the main loops extending about the rear teeth and being spaced far enough from the surfaces of the rear teeth to afford an anchorage for the teeth in a denture, and a second piece of material extended along the

intermediate portion of the body and having its ends located closely together, one of the said ends being engaged with the intermediate portion of the body, and the other of the said ends being engaged with the intermediate portion of the body and with the second piece of material, the said second piece of material being formed into alternating primary and secondary loops, the secondary loops being engaged about the intermediate portion of the body, and forward teeth having openings receiving the intermediate portion of the body, the primary loops being spaced from the surface of the forward teeth to afford an anchorage in a denture.

4. In a device of the class described, an anchor embodying a single piece of material formed into a curved body comprising side members and an intermediate portion, the side members being reversely extended to form forwardly prolonged portions, the forwardly prolonged portions being fashioned into alternating main and auxiliary loops, the auxiliary loops being engaged about the side members, rear teeth having openings through which the side members pass, the main loops extending about the rear teeth and being spaced far enough from the surfaces of the rear teeth to afford an anchorage for the teeth in a denture, and a second piece of material extended along the intermediate portion of the body and having its ends located closely together, one of the aforesaid ends being engaged with the intermediate portion of the body, the other of the aforesaid ends being engaged with the intermediate portion of the body and with the second piece of material, the said second piece of material being formed into alternating primary and second loops, the secondary loops being engaged about the intermediate portion of the body and about the second piece of material, and forward teeth having openings receiving the intermediate portion of the body and the second piece of material, the primary loops being spaced from the surface of the forward teeth to afford an anchorage in a denture.

In testimony that I claim the foregoing as my own, I have hereto affixed my signature.

BAXTER C. SCOTT.
